UNITED STATES PATENT OFFICE.

TORRIS H. ALFREDS, OF CHICAGO, ILLINOIS.

OPERATING MECHANISM FOR WASHING-MACHINES.

1,165,377.

Specification of Letters Patent. Patented Dec. 28, 1915.

Application filed October 28, 1912. Serial No. 723,051.

To all whom it may concern:

Be it known that I, TORRIS H. ALFREDS, a citizen of the United States, and a resident of Chicago, in the county of Cook and State of Illinois, have invented certain new and useful Improvements in Operating Mechanism for Washing-Machines; and I do hereby declare that the following is a full, clear, and exact description thereof, reference being had to the accompanying drawings, and to the letters of reference marked thereon, which form a part of this specification.

This invention relates to an improvement in operating mechanism for washing machines and the like and consists of the matters hereinafter described and more particularly pointed out in the appended claims.

The invention is shown herein as applied to the operation of a washing machine of familiar type consisting of a tub having a hinged top upon which is supported a shaft which depends into the tub and is provided at its lower end with a dolly or dasher adapted for rotary, reciprocatory movement by means of which the clothes and water are first stirred in one direction and then in the opposite direction.

In the drawings:—Figure 1 represents a top plan view of a washing machine provided with my improved operating mechanism. Fig. 2 is a view in side elevation of a washing machine provided with my improved operating mechanism. Fig. 3 is a view representing a transverse vertical section on an enlarged scale taken on a plane indicated by the line 3—3 of Fig. 1. Fig. 4 is a view similar to Fig. 3 illustrating a high speed fly wheel mechanism adapted to be operated in connection with my improved operating mechanism. Fig. 5 is a fragmentary view illustrating a modified form of high speed mechanism adapted to be operated in connection with my improved operating mechanism.

Now referring to that embodiment of my invention illustrated in the drawings, 10 indicates the tub which is supported by legs 10^a, and has its top closed by a suitable lid 11 that is hinged to a stationary member 12 forming a part of the top of the tub, by means of hinges 11^a, 11^b. A wringer-board 10^x is arranged at right angles to the stationary member 12 and also forms a part of the top wall of the tub.

14 indicates the dolly or beater which is non-rotatably connected to a dolly or oper-

ating shaft 13 that is rotatably supported from the top of the hinged lid 11 of the tub. Said shaft has bearing in a sleeve 15^a which projects through an aperture in the lid of the tub, and which is made integral with a plate 15 secured to the outer surface of the tub-lid. To the upper end of the shaft 13 is secured a grooved pulley wheel 16.

To the stationary member 12 of the top of the tub and extending at right angles to the hinge axis of the lid 11, is secured a second base-plate 17 having an upright fulcrum pin 17^a. A double armed bell-crank lever 18 is journaled upon the fulcrum pin 17^a so as to be capable of oscillatory movement in a horizontal plane. Said bell-crank lever 18 comprises a power or operating arm 18^a by means of which oscillatory movement may be imparted to it and two oppositely extending load arms 18^b, 18^b. The outer ends of said load-arms 18^b, 18^b are provided with spaced apertures 18^x. Means are provided for operatively connecting said load-arms to said operating shaft 13 comprising a yielding, non-elastic belt 19 made of leather, rope or steel woven cable, preferably the latter on account of its suitable qualities, which belt is secured at its ends by suitable hook members 19^a, 19^a, to the load arms 18^b, 18^b, by means of one of the apertures 18^x. The said belt is passed around the grooved pulley 16 and is preferably rigidly attached at its center to said pulley so that it will not slip or slide thereon, as by means of a clip 16^a. In said belt are provided, as shown, turnbuckles 19^b, 19^b, adapted to take up slack. The said apertures 18^x, 18^x are arranged in said arm so that the hook members may be shifted from one aperture to another without any adjustment of the belt 19, thus providing for a variation of the angle through which the operating shaft 13 may be rotated without affecting the angle of oscillation of the bell-crank lever.

On that side of the tub body 10 adjacent the fixed top member 12 thereof is located a vertically arranged prime-mover lever 20. Said lever comprises arms 23, 23^a arranged at right angles to each other, and is mounted upon a fulcrum pin 21 fixed upon a bracket plate 22 secured to the upright side wall of the tub body. A balance wheel 25 is rotatably mounted upon a second fulcrum pin 26 formed upon the said bracket plate 22 and is operatively connected to the arm

23 of the lever 20 by means of a link 24. To the arm 23^a of said lever 20 is pivotally secured one end of a universal link 27, the other end of which is pivotally secured to the outer end of the operating arm 18^a of the bell-crank 18. It is apparent that a 5 rocking movement of the prime-mover lever will transmit an oscillatory movement to the bell-crank lever 18 and said movement will 10 impart a rotary, reciprocatory movement to the operating shaft by means of the belt 19 and the grooved pulley 16. To assist in the oscillatory movement of the double armed bell-crank lever 18, I provide upon the 15 power arm 18^a thereof an upright lug 18^y, to which is attached one end of a contractile coiled spring 30, the other end of which is attached to an upright lug 17^x formed upon the base-piece 17, near the inner end thereof. 20 The spring will assist in the movement of the bell-crank 18 each time it passes the center, thereby greatly lessening the power required to move the same to either limit of its movement. The inner end of the said 25 base-piece 17 is formed to provide a rest 17^y for the lid 11 when the same is in its open position. To assist in keeping the belt 19 taut when the lid is in open position, I provide upon that edge of the lid adjacent the 30 stationary member 12, guide-members 31, 31. The guides are so arranged that their lower faces are in the same general plane as that of the grooved pulley 16 and the lateral edges thereof adjacent the member 12 are in 35 line with the center of the hinges 11^a, 11^a. This construction permits the belt to remain taut while the lid 11 is in open position without placing any undue stress upon said belt.

In connection with my improved operating mechanism, I may provide a high-speed mechanism located beneath the tub and to this end I employ a construction, as shown 40 in Fig. 4. In said figure, my improved operating mechanism is indicated by the same reference numeral as before but instead of a 45 balance-wheel 25, I provide a grooved wheel journaled upon said fulcrum pin 26.

Secured to the under side of the bottom 50 wall 10^y of the tub is located a base-plate 36 having a depending stub-shaft 37. Rotatively mounted upon said shaft and secured in such position by means of a nut 37^a is located a fly-wheel 38 of comparatively large 55 diameter. Made integral with said fly-wheel is a grooved wheel 38^a of small diameter around which passes an endless belt 39. The said belt is trained over pulleys 40 and thence around the grooved wheel 35. The pulleys 40 are rotatively supported in a 60 bracket member 41 secured to the tub-body, which is capable of adjustment so that the belt 40 may be maintained in its proper tautness. I may, however, prefer to place the high-speed mechanism upon the side of 65 the tub and to that end I provide a con-

struction such as shown in Fig. 5 and instead of the balance-wheel 25, a spur-gear 45 is journaled upon the fulcrum pin 26 which meshes with a spur-pinion 46 made integral with a fly-wheel 47 mounted upon a fulcrum-pin 48 fixed to an extension 22^a of the bracket plate 22 secured to the side wall of the tub body.

It is readily apparent that a washing machine made in accordance with my invention possesses many advantageous features. The construction described allows of the placing of the lever mechanism on that side of the tub adjacent the fixed top member 12 of the tub, thereby giving the operator a 75 more free access to the interior of the tub besides overcoming the great objection of springing the hinged connection between the stationary top wall of the tub, and the lid, caused by placing the operating mechanism 80 on the lid in a plane parallel to the hinges. This construction acts to evenly distribute the stress to the marginal adjacent edges of the stationary top member and the lid, thus 85 taking the strain off the hinges. In addition the weight of said lid is greatly reduced and this weight reduction is of great consequence both to the operator and the manufacturer. Again, when the lid is raised to an open 90 position the connection between the operating mechanism and the dolly-shaft is not disconnected in any manner and said lid may be open regardless of the position in 95 which the operating mechanism stops. Also the angle of rotation of the dolly-shaft may 100 be adjusted to accommodate a light or heavy load within the tub without disturbing the adjustment of said operating mechanism.

The construction is extremely smooth and noiseless in operation on account of the absence of gearing which also greatly diminishes the danger to the operator. It is particularly adapted for use in connection with high-speed mechanism for the reason 105 that when the tub-lid is open none of said 110 mechanism is within reach or sight of the operator.

While I have described the details of constructions herein shown, I do not wish to be limited thereto except as pointed out in the 115 appended claims.

I claim as my invention:—

1. An operating mechanism for washing machines and the like comprising a fixed support, a prime-mover mounted thereon, a 120 double arm bell-crank lever also mounted thereon and operatively connected with the prime-mover, a hinged support, a rotary, reciprocatory operating shaft vertically disposed in said hinged support, flexible operative connections between said bell-crank lever and said shaft, and a balance-wheel located upon the fixed support and operatively connected with said prime-mover.

2. An operating mechanism for washing 130

machines and the like comprising a fixed support, a prime-mover mounted thereon, a double arm bell-crank lever also mounted thereon and operatively connected with the prime-mover, a hinged support, a rotary, reciprocatory operating shaft vertically disposed in said hinged support, flexible operative connections between said bell-crank lever and said shaft, a balance-wheel and means operatively connecting said wheel to said prime-mover, said means including speed increasing gearing.

3. An operating mechanism for washing machines and the like comprising a rotary, reciprocatory shaft, a double armed bell-crank lever adapted for oscillatory movement, said bell-crank lever comprising a power arm, and transversely extending load arms arranged at right angles to said power arms, means operatively connecting said reciprocatory shaft and said arms, a prime-mover lever and means operatively connecting said lever and said power arm.

4. An operating mechanism for washing machines and the like comprising a fixed support, a prime-mover mounted thereon, a double armed bell-crank lever also mounted thereon and operatively connected with said prime-mover, a hinged support adapted to be swung from a horizontal to a vertical position, a reciprocatory operating shaft vertically disposed in said hinged support, flexible operative connections between said bell-crank lever and said shaft, and means adapted for retaining said flexible operative

connections in proper position when said hinged support is in either a horizontal or vertical position.

5. An operating mechanism for washing machines and the like comprising a fixed support, a prime-mover mounted thereon, a double armed bell-crank lever adapted for reciprocatory movement mounted thereon, and operatively connected with said prime-mover, a second support pivotally secured to said fixed support at their adjacent edges, said support being adapted to be swung from a horizontal to a vertical position, hinges connecting said supports, a vertically disposed reciprocatory operating shaft disposed in said second support, flexible operative connections between said bell-crank lever and said shaft, means adapted for retaining said flexible operative connections in proper position when said hinged support is in either a horizontal or vertical position, said means comprising clips through which said flexible connections extend, said clips being secured to the edge of said second support adjacent the fixed support, the lower lateral edges of said clips being in line with the center of said hinges.

In testimony, that I claim the foregoing as my invention I affix my signature in the presence of two witnesses, this 25th day of October A. D. 1912.

TORRIS H. ALFREDS.
